UNITED STATES PATENT OFFICE.

GEORGE MAULE MARCHANT, OF HUDDERSFIELD, COUNTY OF YORK,
ENGLAND.

SIGHT-FEED LUBRICATOR.

SPECIFICATION forming part of Letters Patent No. 413,759, dated October 29, 1889.

Application filed June 3, 1889. Serial No. 912,997. (No model.)

To all whom it may concern:

Be it known that I, GEORGE MAULE MARCHANT, a subject of the Queen of Great Britain, and a resident of Huddersfield, Yorkshire, England, have invented certain Improvements 5 in Sight-Feed Lubricators, of which the following is a specification.

My invention relates to sight-feed lubricators, such as are employed for lubricating the 10 cylinders of steam-engines and for other purposes where constant lubrication is required.

In the accompanying drawings, which serve to illustrate my invention, Figure 1 is an elevation of a sight-feed lubricator constructed 15 according to my invention. Fig. 2 is a vertical mid-section of the same, showing the operating-piston of the lubricator at its lowest position. Fig. 3 is a section similar to Fig. 2, showing the piston at its highest position. 20 In this view I have not repeated the parts seen at the right in Fig. 2. Fig. 4 is a cross-section illustrating some of the details of construction. Fig. 5 is a detached view of the piston of the lubricator and its operating mechanism.

In the drawings, 1 represents the shell or outer casing of the lubricator, and 2 the usual or any glass sight-tube, through which the drops of oil or lubricant pass on their way to 30 the parts to be lubricated.

3 is an upright cylinder or chamber, in which plays the piston or plunger 4 of the lubricator, and in the wall of this cylinder is formed a vertical slot or opening 5, through which pass 35 studs or pins 6, serving to pin the piston fast to the cams or operating mechanism of the device. This operating mechanism consists of two cams 7 and 8 with spiral faces, the former of which, as before stated, is pinned to 40 the piston 4, and the latter revolves about the cylinder 3, and is provided at its upper edge with a worm-wheel 9, which is in engagement with a worm 10, driven positively and intermittently from a pawl-and-ratchet device outside the casing 1 from the working part of the steam-engine.

In Fig. 1, 11 represents the ratchet-wheel, and 11^a the pawl in engagement therewith, which is borne on the upper end of a bent lever 12, to which reciprocating movement is

imparted from the engine in any suitable way. The rotary motion of the upper cam 8 causes the lower cam 7 to descend by the spiral faces of the same, and with it the piston; but as soon as the cams have reached the position 55 shown in Fig. 5 the piston will have reached the extent of its downward movement, and thus the oil in the chamber 13 at the bottom of the cylinder 3 will be forced or pressed out through an outlet or outlets, as indicated by 60 the arrows in Fig. 2. These outlets may be covered with wire-gauze or the like to prevent any dust or fiber from finding its way to the working parts of the engine. The oil flows from the outlets through a tube or passage 65 13^a (see Figs. 2 and 4) to a nozzle or jet 14, through which it passes to the sight-tube 2, and passes upward through the water or other liquid therein to the top, whence it overflows through an outlet and a second jet or nozzle 70 15 and through a pipe 15^a to the parts requiring lubrication in the direction indicated by the arrows in Fig. 2.

I will now describe the device whereby the oil contained within the outer casing 1 of the 75 lubricator is admitted to chamber 13 below the cylinder 3.

In the passage 13^a, leading from the chamber 13 to the nozzle 14, I arrange a valve 24, the spindle of which passes through the roof 80 of a casing in which the valve-seat is also formed. This casing is surrounded by a perforated tube 23, as seen in Fig. 2. The valve is pressed up to its seat normally by a spiral spring 24^a, arranged beneath it, and the 85 upper end of the valve-stem or spindle is in the path of a wiper or finger 25, secured by screws or the like to the upper cam 8, so that when the cam 8 descends this finger presses down the valve and allows the oil from the 90 inferior of the casing to enter chamber 13, into which it is drawn by the sudden rising of the plunger 4 in the same. When the plunger is forced down by the cams, in order that the oil may be supplied to the parts to 95 be lubricated, the pressure brought to bear by the spring will have pressed the valve up to its seat, and it will thus be kept closed, so that no oil may pass back into the interior of the casing 1.

In order to regulate the amount of oil supplied to the parts at each downward stroke of the plunger 4, I prefer to mount in the cover of the outer casing, above the same, an adjusting-screw 18, the lower end of which comes in contact with a lock-nut 17 on the upper end of the plunger when the latter is raised by the pressure of the spring 16, arranged around the plunger, just beneath the collar of said lock-nut. By screwing the adjusting-screw up or down the extent of movement of the plunger in the cylinder 3 may be varied, and consequently the amount of oil drawn into said chamber 13 below the cylinder and forced through the sight-tube may also be regulated to suit the circumstances.

In order to prevent the water from the tube 2 from being drawn into the chamber 13 when the plunger is on its upstroke, I provide a series of valves, as seen in Fig. 4. In this view, which is a vertical section taken in the axis of the sight-tube, as indicated by the broken line in Fig. 2, the arrows show the course of the oil through the valves and passages.

²⁵ *a* and *b* represent two valves set in the casing and each provided with a spring to keep it pressed down to its seat. The oil flows across the casing through these valves, and at the other side of the casing, opposite the passage 13^a, is turned abruptly and led upward to the nozzle 14, through a small bore or passage *c*. The passage 13^a includes the entire oil-channel from the chamber 13 to the nozzle 14, the bore *c* being a contracted portion thereof. This passage is or may be somewhat devious and branched, its form being governed somewhat by the particular mode of constructing the lubricator. The piston 4 reciprocates, the cam 8 moving it in ³⁵ one direction and the spring 16 moving it in the other direction.

It is not essential to my invention that the spring 16 shall be arranged to lift the plunger and the cams 7 and 8 to press it down. ⁴⁵ The position of these parts may be reversed with equally good results.

Having thus described my invention, I claim—

⁵⁰ 1. In a sight-feed lubricator, the combination, with the outer casing and the cylinder

therein, provided at its base with an enlarged chamber for the reception of the oil for lubrication, and an outlet for the oil from said chamber, the plunger playing in said cylinder and its lower end adapted to enter said chamber and force the oil therefrom, and the operating mechanism of the lubricator, consisting of the cams and springs arranged substantially as set forth, of the valve arranged in the passage leading from the chamber below said plunger, its stem arranged in the path of a projection from one of said cams, whereby the movement downward of said cams opens the valve for the admission of oil to the chamber from the oil-reservoir, substantially as and for the purposes set forth.

⁵⁵ 2. In a sight-feed lubricator, the combination, with the outer casing containing oil and the cylinder arranged therein, and the chamber below said cylinder for the reception of the oil to be fed to the parts to be lubricated, of a valve controlling the admission of oil to said chamber and means, substantially as described, for opening and closing said valve.

⁶⁰ 3. In a sight-feed lubricator, the combination, with the fixed outer casing and the cylinder arranged therein, provided at its base with a chamber and a passage leading thereto for the admission of the oil to be fed, of the plunger in said cylinder, its lower end entering said chamber beneath the cylinder, means, substantially as described, for operating said plunger, and means for varying the stroke of said plunger, consisting of the ⁶⁵ adjusting-screw mounted in the casing, its lower end adapted to press upon the upper end of said plunger and limit the movement thereof.

⁷⁰ In witness whereof I have hereunto signed my name in the presence of two subscribing witnesses.

GEORGE MAULE MARCHANT.
